ARTHUR C. ROWLEY, OF PHILADELPHIA, PENNSYLVANIA, ASSIGNOR TO ASSOCIATED AUTOMATIC SPRINKLER CO., OF PHILADELPHIA, PENNSYLVANIA, A CORPORATION OF DELAWARE.

APPARATUS FOR OPERATING ALARMS OR OTHER DEVICES.

1,138,249.

Specification of Letters Patent.

Patented May 4, 1915.

Application filed March 25, 1914. Serial No. 827,111.

To all whom it may concern:

Be it known that I, ARTHUR C. ROWLEY, a citizen of the United States, and a resident of the city of Philadelphia and State of Pennsylvania, have invented certain new and useful Improvements in Apparatus for Operating Alarms or other Devices, of which the following is a specification.

One object of this invention is to provide an improved apparatus, or retarding device, particularly adapted to be installed in an automatic fire sprinkler or alarm system, between a source of water supply and one or more alarm devices to prevent false alarms due to water hammer or brief pulsations in the water supply, but to effect or permit of the operation of the alarm device or devices as a result of a continuous flow of water from the source of supply through the improved apparatus for a predetermined period.

Other objects of this invention will appear hereinafter.

In the accompanying drawings, Figure 1, is a longitudinal vertical section of an apparatus constructed in accordance with this invention; Fig. 2, a transverse section on line 2—2 of Fig. 1; and Fig. 3, a transverse section on line 3—3 of Fig. 1.

Referring to the drawings, one embodiment of this invention comprises a vertical hollow casing 1 including an enlarged hollow upper portion or head 2 and a reduced hollow lower portion or neck 3 extending downwardly from the upper portion and forming therewith a main receiving compartment or chamber 4 adapted to contain water or other fluid. The lower portion of the casing 1 is provided upon one side with a lateral tubular extension 6 into which is threaded a tubular pipe connection 7 which provides an inlet 8 communicating with the main receiving compartment 4.

When this improved device is connected with an automatic sprinkler system, the inlet 8 is connected to the source of water supply through a suitable pipe controlled by any suitable alarm valve which is normally closed but which is automatically opened in a well-known manner when one or more sprinkler heads have been released, and which is sometimes opened slightly by intermittent variations in the pressure of water in the source of water supply such as

are caused by water hammers or other intermittent pulsations of water. The alarm valve is not shown as such valves are old and well-known in the art. The upper portion of the casing 1 is provided, in this instance, with two outlets 10 and 11 which may be connected respectively to suitable alarms or other devices by suitable pipes 12 and 13. For instance, one outlet may be connected by its pipe 12 to operate an electrical circuit closer, while the other outlets 15 may be connected by its pipe to operate a water motor, or other mechanical device for actuating an alarm. When a water motor is used it is preferably provided with a discharge opening below the level of the corresponding outlet 10 or 11 of the receiving chamber 4 to relieve the pressure in the receiving chamber 4 when the alarm valve is closed.

For preventing a premature operation of the alarms or other devices controlled by this improved apparatus, the inner end of the inlet connection 7 is tapered inwardly and terminates in a flat annular valve seat 20 coaxial therewith. Arranged within the lower portion of the receiving compartment 4 and coaxial with the inlet 8, is a valve 21, which is provided with a flat marginal portion which normally engages against the valve seat 20. The valve 21 is provided 75 with a cylindrical valve stem 22 preferably integral therewith and extending inwardly therefrom coaxially therewith. The valve stem 22 is arranged to fit snugly but slidably in a bushing 23 which is threaded 80 through a partition 24 integral with the exterior walls of the casing 1, and separating the main receiving chamber 4 from a diaphragm or auxiliary chamber 25 formed by a substantially cylindrical lateral extension 26 of the casing 1. This lateral extension 26 is preferably substantially coaxial with the valve stem 22 and is provided upon its outer end with an outwardly extending annular flange 27, the outer surface of which 85 is divided into a flat annular vertical marginal portion 28 and a substantially annular concave portion 29 which extends inwardly from the flat marginal portion 28. Arranged outside of the lateral cylindrical extension 26 and coaxial therewith is an elongated cover 30 provided upon its inner end with an outwardly projecting annular

flange 31, the inner surface of which is provided with a flat vertical marginal portion 32 and with a substantially concave annular portion 33.

5 For moving the valve 20 away from its seat 21, a circular flexible diaphragm 35 made of Monel metal or other similar or suitable material is arranged between the lateral extension 26 and the cover 30. The marginal portion 32 of this diaphragm is securely clamped between the flat marginal surface 28 and 32 of the flanges 27 and 31 by means of bolts 40 projecting through suitable apertures provided therefor in the diaphragm 35 and in the flanges. The diaphragm 35 is provided with a central aperture in which snugly engages the inner end of this valve stem 22 and a narrow annular portion of the diaphragm surrounding its central aperture, 20 is clamped securely against the outer surface of an annular collar 41 provided on the stem 22, by means of a collar 42 surrounding the outer end of the stem, the collar 42 being secured in position by a locknut 43 threaded upon the stem. The cover 30 is provided on its under side with an aperture 44 to prevent an accumulation of pressure in the cover.

The valve 21 is normally pressed against its seat 20 by a spiral spring 45 which is arranged in the cover 30 and in longitudinal alignment with the stem 22, and one end of which surrounds the inner end of the stem 22 and engages against the locknut 43, and 35 the other end of which surrounds a reduced extension 46 on the inner end of an adjusting screw 47 which is threaded axially through the outer end of the cover 30 and which is held in any position of adjustment by means of a locknut 48 which is threaded upon the screw 47 and engages against the outer end of the cover 30, the outer end 49 of the screw 47 being squared or otherwise suitably formed to receive a 45 wrench.

The diaphragm chamber 25 is maintained at all times in communication with the inlet 8, through a comparatively small or restricted passage 55 which extends longitudinally through the valve 21 and the inner portion of the stem 22 and terminates at its inner end in a lateral outlet 56 opening into the diaphragm chamber 25. This restricted passage 55 is provided with one or more 50 branch passages 57 which lead outwardly through the valve 21 and through which communication is maintained at all times between the passage 55 through the valve and the main receiving chamber 4.

60 To permit of a restricted discharge of water from the interior of the casing 1 when the valve 21 is upon its seat 20 and to automatically prevent such discharge when the valve 21 has moved away from its seat to 65 its full open position, the bushing 23 is pro-

vided with an annular recess 60 which is at all times in communication with a discharge passage 61 leading downwardly therefrom through the wall of the casing 1. This annular recess 60 is also in communication 70 with the lower portion of the main receiving chamber 4 when the valve 21 is closed upon its seat 20, through one or more horizontal passages 62 which extend through the inner end of the bushing 23. The discharge passage 61 is so proportioned in comparison with the passages 55 and 57 through the valve that the rate of flow through the discharge passage will be somewhat less than the rate of flow through the valve and into 80 the main receiving chamber 4, when the valve is in its normal closed position, thus producing a differential filling of the main receiving chamber 4. The inner end 63 of the bushing 23 is preferably concave and 85 substantially conical in form and the inner end 64 of the valve 21 is correspondingly formed to fit snugly against the inner end of the bushing 23 and to close the horizontal passage 62 when the valve has been moved 90 a sufficient distance away from its seat 20 by the action of the diaphragm 35 as will be explained hereinafter.

In the operation of this device the valve 21 is normally pressed against its seat 20 by 95 the spiral spring 45 with a force that may be varied by adjusting the screw 47.

When the valve 21 is upon its seat 20, and the alarm valve (not shown) is opened, the water is forced into the inlet 8 and passes 100 through the passage 55, through the valve 21 and its stem 22, and into the diaphragm chamber 25. Some of the water also passes from the passage 55 through the branch passages 57 and into the lower portion of 105 the main receiving chamber 4. The diaphragm chamber 25 and the main receiving chamber 4 are thus gradually filled with water. During this period the water rises above the level of the horizontal outlet passage 62 through the bushing 23, and as long as the water is above the level of one or more of these horizontal passages 62, and while the valve 21 is held against its seat 20, some 110 of the water is discharged from the main receiving chamber 4 through the horizontal passages 62, annular recess 60, and discharge passage 61. By suitably proportioning the transverse sectional areas of these passages 55, 57, and 62, the filling of the main receiving chamber is permitted to proceed only slowly under the retarding action of the discharge passages 62, 60, and 61, as long as the valve 21 is held upon its seat 20. The 115 inward pressure upon the diaphragm which is caused by the action of the spring 45 is so adjusted by means of the screw 47 that the valve 21 is held upon its seat 20 until the diaphragm chamber 25 has been entirely 120 filled with water and until a pressure of 125 130

- about five pounds to the square inch is created in the outlet pipes 12 and 13. After this has occurred, if the pressure in the inlet 8 is maintained the pressure of the water in 5 the diaphragm chamber 25 and main receiving chamber 4 acting through the branch passages 57 in the valve and the longitudinal passage 55 through the valve stem acts to press the diaphragm 35 outwardly and to move the valve 21 inwardly away from its seat 20, and to eventually force the conical inner surface 63 of the valve against the concave end of the bushing 23 thus effecting the full opening of the inlet 8, 10 and closing the discharge passages 62, whereupon all of the water that passes inwardly through the inlet 8 will enter directly into the main receiving chamber 4, and will be effective to operate the alarm devices connected to the outlets 10 and 11 of 15 the upper end of the compartment 3, and an unnecessary waste of water will be prevented. The passages in the device may be so proportioned that a continuous flow of 20 water inwardly through the inlet 8 must be maintained for a predetermined period preferably of about 15 or 20 seconds before the interior of the casing 2 will be filled with water and the alarm devices connected to 25 the outlets 10 and 11 operated, as hereinbefore described. When the flow inwardly through the inlet 8 is stopped by the closing of the alarm valve (not shown) the pressure in the main receiving chamber is relieved 30 and the valve 21 is returned into contact with its seat 20 and the water in the receiving chamber and some of the water in the diaphragm chamber is permitted to drain away through the discharge passage 61. 35
- 40 It is evident, therefore, that this improved device, when used in connection with an automatic fire sprinkler and alarm system, will prevent false alarms from being sounded by water hammer, or by brief fluctuations in pressure in the source of water supply but will respond to operate the alarms when the flow of water is maintained in the device for a predetermined period.
- Although only a single form has been shown 45 in which this invention may be embodied it is to be understood that this invention is not limited in its application to the specific construction described, but might be applied in various forms for various purposes without departing from the spirit of this invention or the scope of the appended claims.
- Having thus fully described this invention, I claim and desire to protect by Letters Patent of the United States:
- 60 1. The combination with means providing a receiving chamber adapted to contain a fluid and provided with an inlet leading into said chamber and a discharge passage leading from said chamber, of a valve normally arranged to oppose a free flow of 65
- fluid through said inlet and means coöperating with said valve and arranged to be actuated under a predetermined pressure in said receiving chamber to move said valve to permit a free flow of fluid through said inlet and to close said discharge passage, 70 said discharge passage being normally in restricted communication with said inlet. 75
2. The combination with means providing a supply chamber adapted to contain a fluid and provided with an inlet leading into said chamber and a discharge passage leading from said chamber, of a valve normally arranged to oppose a free flow of fluid through said inlet and a diaphragm coöperating with said valve and arranged to be actuated under a predetermined pressure in said receiving chamber to move said valve to permit a free flow of fluid through said inlet and to close said discharge passage, 80 said discharge passage being normally in restricted communication with said inlet. 85
3. The combination with means providing a fluid receiving chamber and an auxiliary chamber, and provided with an inlet leading 90 into said receiving chamber and a restricted outlet leading from said receiving chamber, of a reciprocatory member including a valve normally arranged to oppose a free flow of fluid through said inlet, and means connect- 95 ed to said reciprocatory member and arranged to be actuated by a fluid pressure in said auxiliary chamber to actuate said reciprocatory member, said auxiliary chamber being normally in restricted communication 100 with said inlet. 105
4. The combination with means providing a fluid receiving chamber and an auxiliary chamber, and provided with an inlet leading into said receiving chamber and a restricted outlet leading from said receiving chamber, 110 of a reciprocatory member including a valve normally arranged to oppose a free flow of fluid through said inlet, and a diaphragm connected to said reciprocatory member and arranged to be actuated by a fluid pressure in said auxiliary chamber to actuate said reciprocatory member, said auxiliary chamber being normally in restricted communication 115 with said inlet. 120
5. The combination with means providing a fluid receiving chamber and an auxiliary chamber, and provided with an inlet leading into said receiving chamber and a restricted outlet leading from said receiving chamber, 125 of a reciprocatory member including a valve normally arranged to oppose a free flow of fluid through said inlet, and means connected to said reciprocatory member and arranged to be actuated by a fluid pressure in said auxiliary chamber to actuate said reciprocatory member, said auxiliary chamber being normally in restricted communication with said inlet through said reciprocatory member. 130

6. The combination with means providing a fluid receiving chamber and an auxiliary chamber, and provided with an inlet leading into said receiving chamber and a restricted outlet leading from said receiving chamber, of a reciprocatory member including a valve normally arranged to oppose a free flow of fluid through said inlet, and means connected to said reciprocatory member and arranged to be actuated by a fluid pressure in said auxiliary chamber to actuate said reciprocatory member, said auxiliary chamber being normally in restricted communication with said inlet and with said receiving chamber.
7. The combination with means providing a fluid receiving chamber and an auxiliary chamber, and provided with an inlet leading into said receiving chamber and a restricted outlet leading from said receiving chamber, of a reciprocatory member including a valve normally arranged to oppose a free flow of fluid through said inlet, and means connected to said reciprocatory member and arranged to be actuated by a fluid pressure in said auxiliary chamber to actuate said reciprocatory member, said auxiliary chamber being normally in restricted communication with said inlet and with said outlet.
8. The combination with means providing a fluid receiving chamber and an auxiliary chamber, and provided with an inlet leading into said receiving chamber and a restricted outlet leading from said receiving chamber, of a reciprocatory member including a valve normally arranged to oppose a free flow of fluid through said inlet, and means connected to said reciprocatory member and arranged to be actuated by a fluid pressure in
- said auxiliary chamber to actuate said reciprocatory member, said auxiliary chamber being normally in restricted communication with said inlet and with said outlet through said reciprocatory member.
9. The combination with means providing a fluid receiving chamber and an auxiliary chamber, and provided with an inlet leading into said receiving chamber and an outlet leading from said receiving chamber, of reciprocatory means including a valve arranged between said inlet and said outlet, and a diaphragm arranged in said auxiliary chamber and operative under a predetermined pressure in said auxiliary chamber to actuate said reciprocatory means, said auxiliary chamber being normally in restricted communication with said receiving chamber.
10. The combination with means providing a fluid receiving chamber and an outlet chamber, and provided with an inlet leading into said receiving chamber and an outlet leading from said receiving chamber, of reciprocatory means including a valve arranged between said inlet and said outlet, and a diaphragm arranged in said auxiliary chamber and operative under a predetermined pressure in said auxiliary chamber to actuate said reciprocatory means, said auxiliary chamber being normally in restricted communication with said receiving chamber through a passage provided therefor through said reciprocatory means.

In witness whereof I have hereunto set my hand this 23rd day of March A. D., 1914.

ARTHUR C. ROWLEY.
